UNITED STATES PATENT OFFICE.

HERBERT W. BAIRD, OF CLEVELAND, OHIO, ASSIGNOR OF ONE-HALF TO
ALBERT W. MAYERS, OF SAME PLACE.

DESIGN FOR AN ADVERTISING-FRAME.

SPECIFICATION forming part of Design No. 30,493, dated April 4, 1899.

Application filed January 28, 1899. Serial No. 703,740. Term of patent 14 years.

To all whom it may concern:

Be it known that I, HERBERT W. BAIRD, a citizen of the United States, and a resident of Cleveland, county of Cuyahoga, and State of Ohio, have invented and produced a new and original Design for Advertising-Frames, of which the following is a specification, reference being had to the accompanying drawing, forming a part thereof.

10 The drawing represents a front elevation of an advertising-frame, illustrating my design.

The leading feature of said design consists of a rectangular holder divided into a number 15 of advertising-spaces of rectangular conformation symmetrically disposed about a central circular figure and having other circular figures disposed equidistantly from such central figure and from vertical and horizontal 20 axes of the said frame, as illustrated in the drawing.

The body of the frame is divided by a number of vertical and horizontal strips into a

number of advertising-spaces of varying size and of rectangular conformation, as before 25 stated, spaces of equal size and same shape being located at equal distances on either side of the vertical or horizontal axis of the frame, and said frame is surmounted by ornamentation.

30 In the center of the frame is a circular space, about which the rectangular spaces are grouped, which is occupied by a clock-dial. In each of four rectangular spaces of equal size, located equidistantly from the center of the clock-dials, is a circular space also covered by glass.

What I claim is—

35 The design for an advertising-frame, substantially as shown and described.

Signed by me this 25th day of January, 1899.

HERBERT W. BAIRD.
